UNITED STATES PATENT OFFICE.

SAMUEL HUFSCHEMID, OF PATERSON, NEW JERSEY.

ROTARY ENGINE.

1,255,169.

Specification of Letters Patent.

Patented Feb. 5, 1918.

Application filed August 3, 1917. Serial No. 184,320.

To all whom it may concern:

Be it known that I, SAMUEL HUFSCHEMID, a citizen of the United States, residing at Paterson, in the county of Passaic, State of New Jersey, have invented certain new and useful Improvements in Rotary Engines; and I do declare the following to be a full, clear, and exact description of the invention, such as will enable others skilled in the art to which it appertains to make and use the same.

This invention is an improvement in engines and has particular reference to a rotary steam engine.

An object of the invention is to provide a simple and inexpensive engine in which the valves thereof are operated by an improved actuating mechanism whereby to feed steam into the cylinders of the engine and, at intervals, check said feed thereto.

The inventive idea involved is capable of receiving a variety of mechanical expressions, one of which, for the purpose of illustrating the invention, is shown in the accompanying drawing, wherein:

Figure 1 is a side elevation of an engine constructed in accordance with the invention.

Fig. 2 is a transverse sectional view through one of the cylinders of the engine.

Fig. 3 is a longitudinal section through the engine.

In the drawing the numeral 5 indicates the base of the engine upon which a pair of cylinders 6 are mounted, it being understood that any number of cylinders desired may be employed. The shaft 7 is extended through the several cylinders and has mounted thereon a rotor 8 for each cylinder provided upon its periphery with an abutment 9 against which the live steam impinges and drives the rotor around until the same passes the exhaust pipe 10 in the cylinder, the abutments 9 of each rotor being preferably arranged at diametrically opposite points to each other with relation to the peripheries of said rotor.

Each cylinder 6 is preferably provided with a valve casing 11 on the top thereof into which extends a steam feed pipe 12, the lower end of said pipe being mounted in the upper end of an angular passage 13 formed in the vertical slidable valve 14 whereby the steam entering the pipe 12 will pass through said passage and into the chamber of the cylinder. The valve 14 is slidably mounted

upon the pipe 12 and carries a stuffing box or gland 15 which prevents leakage of the steam from the cylinder through the valve and into the upper portion of the casing 11. Each of the valves 14 is preferably formed of a substantially rectangular block, the lower surface of which is curved as indicated at 16 and normally engages the periphery of the rotor 8, being yieldably held in such position by a coil spring 17 surrounding the pipe 12 and interposed between the upper surface of the valve and the upper end of the casing 11.

The mechanism for operating each valve preferably comprises a pair of vertically disposed rods 18 having their lower ends secured in the valve and slidably engaging the upper end of the casing 11, the upper ends of said rods carrying a contact plate 19 for a purpose which will presently appear. The valve casings 11 preferably have extending therefrom the diagonal bearings 20 supporting the horizontal shaft 21 having a gear 22 on one end adapted to mesh with a similar gear 23 carried by the upper end of the diagonally disposed shaft 24 mounted in bearings 25 and having its lower end provided with a beveled gear 26 meshing with a similar gear 27 carried by one end of the shaft 7. The shaft 21 carries a pair of arms 28, one for each cylinder, each of which is provided upon its free end with a roller 29 adapted to intermittently contact the adjacent end of a rocking element 30 pivoted in a bracket 31 carried by the top of the valve casing. Each of the rocking elements 30 is provided with a pair of cams 32 and when the shaft 21 is driven in one direction one of the cams 32 will engage and raise the plate 19 and thus lift the valve 14 while the other cam 32 will be similarly actuated when the shaft is driven in the opposite direction.

It will be seen from the foregoing description that when the parts are in the position shown in Fig. 2, the valve 14 will have just been returned to its normal position and steam entering the pipe 12 will pass through the passage 13 and against the abutment 9 and thus drive the rotor. After the abutment has passed the exhaust pipe 10 before the same can engage the valve 14 the arm 28 will strike the rocking element 30 and raise the plate 19 so as to lift the valve 14 out of the path of movement of the abutment 9 and at the same time check the flow of

steam through the passage 13 until said abutment has passed the valve and reached the position shown in Fig. 2.

What is claimed is:—

- 5 In a rotary steam engine, the combination of a plurality of cylinders, reciprocating valves for feeding the steam thereto, rods extending from each of said valves, a plate carried by the free ends of the rod of each valve, a rocking element having cam surfaces adapted to engage said plate, a shaft supported by said cylinders, radially dis-

posed arms carried by said shaft each of which is adapted to contact the adjacent rocking element whereby to reciprocate the 15 adjacent plate and actuate the valve to which it is connected, and means for driving said shaft.

In testimony whereof, I affix my signature in the presence of two witnesses.

SAMUEL HUFSCHEID.
